UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,970, dated November 8, 1892.

Application filed October 10, 1892. Serial No. 448,454. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of this design consists of a series of ornamental scrolls and lines forming connected panels with a vase-like ornament filled with flowers and leaves arranged in the center of each of said panels and cornucopia-shaped ornaments filled with flowers and leaves springing outwardly on each side of said vase-like ornaments, as represented in the accompanying drawing. The ornamental scrolls and lines forming the ad-

jacent sides of two panels are connected by 20 small fleur-de-lis-shaped ornaments, and from these ornaments the scrolls and lines diverge to the right and left in graceful curves to form connecting side panels.

The design is printed in any desired color 25 or colors or in gilt or bronze and colors upon tinted paper of any desired color having either a plain or figured background.

What I claim is—

The design for wall-paper herein shown and 30 described.

Witness my hand this 7th day of October, 1892.

CHARLES BOOZE.
